US00D587486S

(12) United States Design Patent
Greiner

(10) Patent No.: US D587,486 S
(45) Date of Patent:  *Mar. 3, 2009

(54) SWIVEL ORGANIZER

(75) Inventor: Lori Greiner, Chicago, IL (US)

CN 2421894 Y 3/2001

(73) Assignee: For Your Ease Only, Inc., Chicago, IL (US)

(*) Notice: This patent is subject to a terminal disclaimer.

U.S. Appl. No. 11/768,979, filed Jun. 27, 2007, Title "Tri-Fold Mirror Organizer", Inventor Lori Greiner.

() Term: 14 Years

(21) Appl. No.: 29/295,115

Primary Examiner—Caron Veynar

(22) Filed: Sep. 21, 2007

Assistant Examiner—Ricky Pham

(51) LOC (9) Cl. 06-04

(74) Attorney, Agent, or Firm—Fredrikson & Byron, P.A.

(52) U.S. Cl. D6/437

CLAIM

(58) Field of Classification Search D6/397,

D6/425–426, 429, 432–448, 455, 470, 474, D6/477–480, 484, 559; D23/342; D99/35; 108/103; 211/85.2, 95, 163; 232/43.2; 242/559.3; 312/107–108, 114, 138.1, 194, 198, 204, 312/249.4, 257.1, 263, 278–279, 293.2, 305, 312/321.5, 334.36, 348.4

See application file for complete search history.

(56) References Cited

I claim the ornamental design for a swivel organizer, as shown and described.

DESCRIPTION

U.S. PATENT DOCUMENTS

FIG. 1 is a perspective view of my new design for a swivel organizer;

FIG. 2 is a perspective view of my new design for a swivel organizer with the top portion slightly rotated;

FIG. 3 is a side perspective view thereof with side and back doors open, the other side perspective view being a mirror image of that shown;

FIG. 4 is a front elevation view thereof with all doors closed;

FIG. 5 is a right side elevation view thereof with all the doors closed;

FIG. 6 is a rear elevation view thereof with all the doors closed;

FIG. 7 is a left side elevation view thereof with all the doors closed;

FIG. 8 is a top plan view thereof; and,

FIG. 9 is a bottom plan view thereof.

The broken lines shown in the drawings are for illustrative purposes only and form no part of the claimed design.
